UNITED STATES PATENT OFFICE.

ALCORN RECTOR, OF NEW YORK, N. Y., ASSIGNOR TO RECTOR GAS LAMP COMPANY, OF NEW YORK, N. Y., A CORPORATION OF NEW YORK.

JETTING METHOD OF COMBUSTION.

1,144,784.

Specification of Letters Patent. Patented June 29, 1915.

Application filed September 26, 1910, Serial No. 583,775. Renewed May 18, 1915. Serial No. 29,236.

To all whom it may concern:

Be it known that I, ALCORN RECTOR, citizen of the United States, residing at New York city, in the county and State of New York, temporarily residing in the city of Pittsburgh, in the county of Allegheny and State of Pennsylvania, have invented certain new and useful Improvements in Jetting Methods of Combustion, of which the following is a specification, reference being had therein to the accompanying drawings.

This invention relates to what may be called a jetting or spraying method of combustion of any gaseous fuel, whether a gas; the mixture of gas and air, or a vapor of oil, for examples.

The different forms of apparatus herein shown form the subject-matter of my applications Serial Nos. 583,776 and 583,778, both filed Sept. 26, 1910.

The objects of this method are to produce intense heat for various industrial purposes, such, for example, as in smelting, reduction, glass-making and cement-burning apparatus; and to improve combustion.

In the accompanying drawings, illustrating the principle of this method by various forms of apparatus and in the best modes now known to me, both in relation to gas or gaseous fuel and also in relation to oil vapor, Figure 1 is a central, vertical section of a form of heating apparatus adapted for the burning of a gas or gaseous mixture according to the present method. Fig. 2 is another form of heater, partially in elevation and partially in section, for use in burning a gas or gaseous fuel by the present method.

The apparatus shown is not herein claimed, because it forms the subject-matter of my application Serial No. 583,776, of even date herewith.

Referring to the accompanying drawings (Fig. 1), 30 is a bunsen provided with the usual air regulator 30^a and discharging into a casing 31 provided with a centrally imperforate wall and a plurality of surrounding perforations 33, the imperforate portion being indicated by 32 and the wall by 34, which extends laterally beyond the casing 31 to form a support for casing 35 located thereon and containing a combustion chamber. Within the combustion chamber there is mounted a supply pipe 36 having an imperforate lower end preferably opposite the

imperforate portion 32 of wall 34 and provided with a plurality of lateral perforations 37 all around its annular wall. From the combustion chamber within casing 35, exhaust pipes 38 for products of combustion lead to the casing 39 of vacuum creating and maintaining device 40 provided with an exhaust port 39^a. Casing 35 is provided with a cover 41, which may be removed for igniting the fuel contained in the combustion chamber. The supply pipe 36 is provided, at its end, exteriorly of casing 35, with a screw cover 42 having a threaded shank 44 that screws into the cross-bar 43 of the projecting end of the supply pipe. It is obvious that the air regulator 30^a may be closed to prevent access of air to the bunsen 30, in which case its pipe may be used for conveying unmixed gas into the chamber 31. It is also obvious that the screw cover 42 may be entirely removed to allow free supply of air or other combustion-supporting gas, such as oxygen, for example, to the combustion chamber through the radial perforations 37; and that both the air regulator 30^a and the cover 43 may be regulated to vary the amount of air admitted past them.

The casing 35 may be of any shape, size or contour adapted for any purpose, such as for heating by radiation, or be formed as a member of any desired kind of apparatus for any desired purpose.

When the exhaust fan is in operation and the mixture of gas or gas and air coming in through the bunsen 30 with the combustion-supporting gas supplied through pipe 36 and entering the combustion chamber through the multitude of preferably small perforations 37 is ignited, very intense heat is obtained, the products of combustion being continuously removed from the vicinity of the flame and out of the combustion chamber during combustion. The gaseous fuel entering the chamber of casing 31 is jetted upwardly for a considerable distance into the combustion chamber, wherein it is intimately mixed with the combustion-supporting gas which is jetted radially from the tube 36. This cross-commingling of the jetted or sprayed gaseous fuel and combustion-supporting gas effects a most thorough mixture thereof, which is greatly favorable to perfect combustion.

In Fig. 2 I show another form of apparatus useful in burning gas or gaseous fuel, wherein the same is jetted into intimate mixture in a combustion chamber with 5 therein jetted combustion-supporting gas or air. In this form of apparatus, bunsen 230, provided with an air-controller 230^a, communicates with an enlarged head 231 containing a chamber of considerable capacity 10 as compared with the cross-sectional area of the bunsen, and in which the air or gas, or mixture of air and gas, coming in through the bunsen, is received. Opposite the mouth of the bunsen is located, the imperforate 15 wall of the burning-plate 232, which is formed with a central tubular extension 236 of which the wall 232 is an integral part. The transverse plate 233, frequently perforated at 234, serves as a partition between the gaseous fuel-receiving chamber of casing 231 and the combustion chamber 235 which surrounds the central tubular projection 236 and lies between the burning-plate 232 and the perforated plate 233. Exhaust pipes 238 20 for the products of combustion lead from the combustion chamber to the casing 239 of vacuum creating and maintaining device 240, the casing having an exhaust port 239^a. The top of the casing of the combustion 25 chamber is shown provided with a form of electrical ignition device 241 for igniting the gaseous fuel as it is jetted or sprayed through the perforations 234 into the combustion chamber, where it is mixed with air, oxygen 30 or any suitable combustion-supporting gas, 35 that is jetted into the combustion chamber through the perforations 237 in the lower end of the central tubular projection 236.

It will be observed that the jets of the 40 combustible fuel and the jets of the combustion-supporting gas are at an angle one to the other, so that a very intimate mixture of the combustion-supporting gas and of the gaseous fuel is obtained in the combustion 45 chamber, wherein the mixture is ignited and the products of combustion withdrawn from the combustion chamber through the exhaust pipes 238 by the vacuum producing and maintaining device, under a rapid movement thereof, given by a suitable power connection, not shown.

In all forms of my invention I have shown the exhaust pipe leading to the casing for the vacuum producing and maintaining device as broken away, to indicate the fact that 55 in ordinary installations, and, generally speaking, in all manufacturing installations, the vacuum producing and maintaining device is located at a point substantially 60 distant from the combustion chamber.

It will be observed that, in all forms of the apparatus shown, the gaseous fuel and the combustion-supporting gas (whether oxygen, for example, or air is more usual,) 65 are introduced at a central point of a wall

of the casing containing the combustion chamber, so that the latter, in effect, extends in all directions laterally of the combustion point; except, however, that this exists in a modified degree in the apparatus shown in Fig. 2. While what may be called the central introduction of the combustion-supporting gas or air is not essential, it is very desirable in many installations, as it secures an incandescent mass that extends outwardly for a considerable distance from the point or points at which the combustion-supporting gas is introduced; in other words, it secures a lateral annular expansion of the flame, and is therefore advantageous for many purposes, especially where a large wall area is to be heated.

In the form of apparatus shown in Fig. 2, the heating-plates, as well as the whole apparatus, may be of any size, shape and material desired; and what I have said of the, advantages of the method as practised by apparatus such as is illustrated in Fig. 1 applies to the operation of apparatus such as illustrated in Fig. 2.

It will be observed that the gaseous fuel is burned in a partial vacuum created in the combustion chamber by the artificial suction, and while the fuel is in a highly attenuated molecular condition in consequence 95 of the suction.

The artificial suction apparatus is operable to secure a uniform, continuous suction.

The word artificial is used in this specification in contradistinction to natural draft means.

What I claim is:—

1. The method of combustion which consists in forming a partial vacuum at the place of combustion, drawing air and gas thereto in a rarefied condition in separate jets, mixing the same and then burning the rarefied mixture.

2. The method of combustion which consists in forming a partial vacuum at the place of combustion, causing air and gas to be rarefied, drawing air and gas in separate jets, mixing the same together at the place of combustion, burning the said mixture in its rarefied state and forcibly withdrawing the products of combustion.

3. The method of combustion which consists in simultaneously creating and maintaining a partial vacuum at the place of combustion, cross jetting gases at an angle to each other, mixing and sustaining the gases in a rarefied state, burning the mixture and forcibly removing the products of combustion.

4. The method of combustion which consists in simultaneously producing a partial vacuum at the place of combustion, drawing a jet of mixed air and gas and a jet of air thereto at angles to each other in a rarefied
